UNITED STATES PATENT OFFICE

151,807

DESIGN FOR A WINE BOTTLE

Hyman C. Berkowitz, Newton, Mass.

Application March 7, 1947, Serial No. 137,445

Term of patent 14 years

(Cl. D58—8)

To all whom it may concern:

Be it known that I, Hyman C. Berkowitz, a citizen of the United States, residing at Newton, in the county of Middlesex and Commonwealth of Massachusetts, have invented a new, original, and ornamental Design for Wine Bottle, of which the following is a specification, reference being had to the accompanying drawing, forming part thereof.

In the drawings,

Fig. 1 is a front elevation of a bottle showing my new design;

Fig. 2 is a side elevation thereof looking to the left of Fig. 1; and

Fig. 3 is a section on line 3—3 of Fig. 1.

I claim:

The ornamental design for a wine bottle, substantially as shown.

HYMAN C. BERKOWITZ.
